UNITED STATES PATENT OFFICE

FRED A. PARSONS, OF MILWAUKEE, WISCONSIN

FURNITURE SHOE

Application filed March 24, 1928. Serial No. 264,310.

This invention relates to improvements in furniture shoes.

It is the primary object of this invention to provide a novel and improved shoe for use on furniture legs in lieu of casters, which will be noiseless on hard wood or tile floors or the like, will reduce friction to a minimum upon such floors, and will likewise slide easily upon rugs and carpets.

It is a further object of the invention to provide a shoe of low cost having a replaceable felt pad arranged for contact with the floor, the shoe being so designed as to provide a holder for the pad which cannot mar or scratch any floor with which it may come in contact due to wear or removal of the pad.

It is a further purpose to provide a shoe so formed and mounted as to accommodate itself to any inequalities in the surface with which the shoe is engaged.

In the drawings,

Figure 1 is the side elevation of a device embodying this invention applied to the lower end of the leg of a piece of furniture;

Figure 2 is an axial section through the device shown in Figure 1;

Figure 3 is an axial section through a modified device representing a slightly different embodiment of the invention;

Figure 4 is a view partially in side elevation and partially in axial section showing a modified form of mounting for that form of my invention which is illustrated in Figs. 1 and 2.

Like parts are identified by similar reference numerals throughout the several views.

The leg of a piece of furniture is represented at 5. The shoe embodying this invention is applied to the bottom of the leg in each of the views and comprises a shell 6, a replaceable pad 7 made of some compressed fibrous material such as felt or the like, and means for anchoring the shell to the leg which may comprise a screw such as is shown at 8 in Figure 2 or a shank such as appears at 9 in Fig. 4.

The shell 6 is formed from sheet metal by spinning or die stamping to provide a con-

vex upper surface at 10 for engagement with the lower end of the leg. The convexity of this surface makes it possible for the shoe to adjust itself to rest solidly upon any supporting surface irrespective of the irregularity of such surface within the capacity of the shell to oscillate upon its mounting.

The bottom of the shell at 11 is substantially flat to provide a considerable area of supporting surface in order to avoid marring a floor upon such occasions as may occur when the felt pad 7 is absent or worn to such a degree that it will not sustain the weight of the furniture. The inner margin 12 of the shell curves slightly upwardly from the plane of the flattened lower surface 11 to avoid any possibility that roughness of the margin might produce scratches on the floor. The upturned margin performs the further function of firmly retaining a pad 7 of the proper diameter. It will be noted that the pad is of slightly greater diameter than the inner peripheral margin 12 of the shell so that when the pad is thrust into the shell it will be additionally compressed at the point where it is engaged by margin 12 and such compression tends to form a crease or groove in the periphery of the pad as is clearly shown in Figs. 2 and 3 and thereby the pad is rather firmly retained within the shell without, however, being impossible of replacement.

The upper portion of the shell is pierced at its axis by an aperture 13 through which extends the screw 8 or the neck portion 14 of the stem 9, as the case may be. The head of the screw 8 or the head 15 of the stem 9, respectively, operate to hold the parts in engagement while permitting considerable freedom of relative tilting movement so that the shoe may accommodate itself to any normal inaccuracies in the floor or supporting surface. In tile floors, for example, there are frequently depressions and irregular surfaces varying from the horizontal by several degrees. The loose engagement between the shoe and its anchoring means, together with the fact that the upper surface of the shoe is pronouncedly convex, results in permitting the shoe to accommo-

date itself to such irregularities by tilting upon the anchoring means and receiving the load of the furniture leg 5 at some point other than its axis.

- 5 It will be understood that where the anchoring means comprises a screw 8, the screw will be driven directly into the bottom of the leg 5, as clearly shown in Fig. 2, and where the anchoring means comprises the stem 9 such stem will be received into a hole 16 in the furniture leg which is preferably provided with a standard sheet metal socket 17 such as is commonly used for casters, the socket being provided with 15 flexible fingers at 18 to engage the enlarged ball 19 at the end of the stem 9.

It is very easy to remove and insert the felt pads 7 in devices shown in Figs. 1, 2, and 4, and consequently it will not ordinarily be necessary to provide any special means of access to the anchoring device. If desired, however, the pad may be made annular as shown at 27 in Fig. 3 and provided with a central thimble at 28 of less axial extent than the pad. The axial position of the thimble is fixed by expanding its ends into the pad as shown at 29. This thimble permits the ready introduction of a screw driver to reach the head of screw 8, or a riveting tool to form the head 15 on a stem or shank such as illustrated at 9 in Fig. 4. A desired clearance between the furniture leg and the head of the anchoring device is insured where screws are used by the use of the sleeve 30 which is shown in Figs. 2 and 3. In the Fig. 4 construction the length of the neck portion 14 provides the desired clearance.

It will be obvious that the device herein described as embodying my invention responds fully to the objects above specified. It will be found that a compressed felt pad will slide with great freedom upon a polished floor and will even slide across a carpet or a rug more easily than some casters. Devices embodying this invention are standardized for use either with screws or with the conventional stems for replacing casters, there being no change necessary in the shoe itself to adapt it for use with either type of anchoring means.

The felt pads are almost instantly replaceable without tools and are firmly held in place when once inserted into the shell 6. 55 Even if the felt pad becomes lost or excessively worn, however, it will be obvious that the shell is incapable of doing any damage even to a highly polished surface due to the fact that no sharp edges are exposed and that a substantially flat supporting surface of considerable area is provided for contact with the floor.

I claim:

1. In combination, a member provided at 55 its top with means of attachment to an ar-

ticle to be supported thereby and provided at its bottom with a recess, and a pad of relatively soft material receivable in said recess and of such dimensions as normally to project therefrom and to provide a primary supporting surface, said member being provided with substantially plane non-abrasive means of substantial area having a rounded margin and normally supported by said pad but arranged to form a secondary supporting surface closely adjacent the supporting surface of the pad and simultaneously available when said pad becomes worn or yields under excessive load.

2. In a device of the character described, the combination with a load sustaining member provided with means for attachment to an article to be supported and provided below said means with a relatively smooth surface of substantial area upwardly relieved within its margins for the non-abrasive support of load imposed by such article, of means about which said surface is disposed for retaining and confining a pad, and a pad of relatively compressible material confined within said means and normally projecting below said surface, whereby to be adapted primarily to receive and support load to which said member is subject, the said supporting surface of said member, however, being simultaneously available to receive said load upon the yielding or destruction of said pad.

3. In a device of the character described, the combination of a load bearing shell having a convexly domed top portion provided centrally with means for attaching it to furniture requiring support, said means being flexibly jointed whereby to provide for relative movement between said shell and furniture supported thereby, an annular base for said shell providing a central aperture and an annular and substantially flat surface about said aperture of sufficient area for the support of a substantial load, said surface being non-abrasive and upwardly curved at its respective margins, a non-metallic and highly compressible pad receivable within said aperture and of such dimensions as to be constricted by the inner margin of said surface and to project normally below said surface while contacting with a portion of said shell thereabove, said surface being available at all times to take the load from said pad when said pad disintegrates or yields excessively under load.

4. A device for supporting an article of furniture, or the like, comprising the combination with a member attached underneath said article and provided with a substantially flat bottom surface terminating in a centrally and upwardly projecting margin, of a pad removably confined within said margin to normally project beneath said surface.

5. In a support for an article of furniture or the like, the combination of a member attached underneath said article and having a convexly domed top surface portion together with a flat bottom surface portion having an upwardly directed inner margin, and a yieldable pad within said margin and normally projecting beneath said flat surface.
- 10 6. In a device for supporting an article of furniture or the like, the combination with a fitting underneath said article having a central aperture and providing about said aperture a substantially flat bottom surface portion curving upwardly at its margins, of a relatively compressible pad mounted in said aperture and normally projecting below said bottom surface to support said article, said surface being available simultaneously 15 with said pad to support said article when said pad becomes worn or excessively compressed.
